SMOKING APPLIANCE

Walter L. Webster, Los Angeles, Calif.

Application September 7, 1949, Serial No. 114,353

1 Claim. (Cl. 131—174)

1

This invention relates to a smoking appliance, and more particularly to a device for safely holding lit cigarettes or cigars, both during the smoking of a cigarette, or when the device is placed on a support during smoking intervals.

The object of the invention is to provide a smoking appliance which includes a post for supporting a lit cigarette or cigar over an ashtray so that the ashes will safely drop into the ashtray and not onto a table top or other article of furniture.

Another object of the invention is to provide a smoking appliance which includes a cigarette supporting post that has a tray connected thereto for receiving ashes from the cigarette, the post being detachably connected to a base and the ashtray being detachably connected to the post whereby the post can be held in the user's hand when smoking the cigarette.

A further object of the invention is to provide a smoking appliance which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a perspective view of the smoking appliance, according to the present invention;

Figure 2 is a sectional view taken on the line 2—2 of Figure 1;

Figure 3 is a top plan view of the ashtray;

Figure 4 is a side elevational view of the spring clamping member.

Referring in detail to the drawings, there is shown a smoking appliance which includes a horizontally disposed base 10 that has projecting upwardly therefrom a vertically disposed stud 11. An open ended hollow or tubular post 12, constituting a hand grip, has its lower end snugly seated over the stud 11. The post 12, preferably, has its exterior in the shape of a hexagon, as best seen in Figure 1.

Detachable supported or connected to the post 12 is a tray 9 for receiving or collecting ashes therein. The tray 9 is provided with a hexagonal shaped hole or opening 13, Figure 3, and the post 12 snugly engages with and projects through the opening 13.

For supporting a lit cigarette 17 above the ashtray 9, a spring clip or clamp 14 is provided. The clip 14 is preferably fabricated of a strip of resilient metal and bent meditately to provide a pair of legs 15 and 16 which are adapted to hold the lit cigarette 17 between end portions thereof; the end portions, preferably, being oppositely and outwardly bowed and inwardly folded upon themselves, substantially as shown in Figures 1 and 2.

From the foregoing, it is apparent that a smoking appliance has been provided which will safely

support a lit cigarette or cigar 17. Thus, with the smoking appliance assembled as shown in Figures 1 and 2, the lit cigarette 17 can be readily positioned between the legs 15 and 16 of the clamp 14, so that the ashes will fall into the ashtray 9 and not onto the clothes of the user, a table top or the floor. Further, if desired, the user can readily slide the tray 9 off of the post 12, and the post 12 can be readily detached from the stud 11 whereby the post 12 can be held in the user's hand while the user smokes the cigarette 17, or the device may be so held while the parts are in assembly.

The base 10 is fabricated of any suitable material such as rubber and the prongs of the clamp 14 can be readily spread by the user's fingers when a cigarette is to be placed or removed therefrom. It is to be noted that the post 12 is provided with a cylindrical bore 18 therein. The tray 9 may be fabricated of any fire-proof material. The device of the present invention thus provides a means for holding a cigarette over an ashtray whereby the lit cigarette will not damage a table top and further the cigarette butt will be prevented from accidentally falling or slipping into the ashtray.

What I claim:

In a smoker's appliance, a flat base having a stud integral with and rising from the center of said base, a tubular post vertically mounted on said stud, an elongated relatively narrow ash receptacle having a bottom opening adjacent one of its ends snugly engaged by said post, said receptacle being positioned below the top end of said post and having its bottom wall sloping upwardly from the said one end to the other of its ends to facilitate the emptying of ashes therefrom, and clamping means seated in the top end of said post to support the lit end of a cigarette above and within the confines of said receptacle.

WALTER L. WEBSTER.
